CLAIM

The ornamental design for a sex toy, as shown and described.

DESCRIPTION

FIG. 1 is a front perspective view of a sex toy of Embodiment 1, showing my new design;

FIG. 2 is a rear perspective view thereof of Embodiment 1;

FIG. 3 is a front view thereof of Embodiment 1;

FIG. 4 is a rear view thereof of Embodiment 1;

FIG. 5 is a left side view thereof of Embodiment 1;

FIG. 6 is a right side view thereof of Embodiment 1;

FIG. 7 is a top view thereof of Embodiment 1;

FIG. 8 is a bottom view thereof of Embodiment 1;

FIG. 9 is an enlarged detail view of area 9 in FIG. 1;

FIG. 10 is a front perspective view thereof of Embodiment 2;

FIG. 11 is a rear perspective view thereof of Embodiment 2;

FIG. 12 is a front view thereof of Embodiment 2;

FIG. 13 is a rear view thereof of Embodiment 2;

FIG. 14 is a left side view thereof of Embodiment 2;

FIG. 15 is a right side view thereof of Embodiment 2;

FIG. 16 is a top view thereof of Embodiment 2;

FIG. 17 is a bottom view thereof of Embodiment 2; and,

FIG. 18 is an enlarged detail view of area 18 in FIG. 10.

The dash-dot-dash broken lines encircling the enlarged views are for annotative purposes only and form no part of the claim thereof.

1 Claim, 18 Drawing Sheets
